UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

DUMPING-CAR-DOOR-OPERATING MECHANISM.

1,224,797.

Specification of Letters Patent. Patented May 1, 1917.

Application filed October 25, 1915. Serial No. 57,748.

To all whom it may concern:

Be it known that I, JOHN M. ROHLFING, residing at St. Louis, Missouri, and being citizen of the United States, have invented 5 certain new and useful Improvements in Dumping-Car-Door-Operating Mechanism, of which the following is a full, clear, and exact description, such as will enable others skilled in the art to which it appertains to 10 make and to use the same, reference being had to the accompanying drawings, which illustrate the preferred form of the invention, though it is to be understood that the invention is not limited to the exact details 15 of construction shown and described, as it is obvious that various modifications thereof will occur to persons skilled in the art.

In said drawings:

Figure 1 is a composite view of a car embodying the novel features of the invention, 20 being in side elevation at the right and a central longitudinal vertical section at the left.

Fig. 2 is a plan view of a portion of the car with a greater part of the flooring removed, to show the operating mechanism, 25 the doors being closed.

Fig. 3 is a similar view of the corresponding parts at the opposite side of the hopper, 30 one of the doors being shown in open position.

Fig. 4 is an enlarged section taken on line 4-4 of Fig. 2 and shows the position of the parts when the doors are closed.

Fig. 5 is a similar section, but of the corresponding parts on the opposite side of the hopper being taken on line 5-5 of Fig. 3 35 and showing the position of the parts when the doors are open.

Fig. 6 is a side elevation of the transmission rod arrangement between the side and the intermediate sills, a portion of the side sill being broken away to show the transmission gearing in the position assumed when 40 the doors are closed.

Fig. 7 is a vertical transverse section through approximately one half of the car showing the locking mechanism and the winding arrangement; and

Fig. 8 is a perspective view of the door lock supporting bracket which is arranged between the draft sills and under the sloping end sheet of the hopper.

The present invention relates to car door

operating mechanism, and is of a type that 55 is well adapted for use in drop bottom gondola or ore cars, and it has for an object a provision of means for locking and supporting doors which are hinged near or at the sides of a car, and whose free ends are 60 adapted to meet and close the discharge opening when the doors are in a raised position.

It is also contemplated to provide means for raising the doors in a car wherein it is 65 difficult or impossible to arrange the lifting means so that it will exert a uniform influence on opposing sides of said doors, and mechanism is supplied to compensate for the lack of uniformity, causing the doors to 70 be properly closed along all of their edges at the completion of the winding and locking operations.

Another object is to securely lock the doors in place and to provide for a simultaneous 75 operation of locks disposed on opposite sides of the doors.

Insurance against unintentional actuation of the door locking means is provided for, and the design precludes the accidental release of the doors due to swaying or other movements of the car during the course of 80 its travel.

The actuation of the door operating means is conveniently and safely accomplished from the sides of the car, avoiding 85 the danger of accidents to men engaged in discharging the lading.

Other advantages will appear hereinafter and are parts of the present invention. 90

Referring specifically to the parts, the chains 10 for raising the doors are adapted to be wound upon a shaft 11 located outside of the hopper and toward one end of the car, and disposed transversely thereof. 95

In Fig. 2, winding shaft 11 is shown as broken away shortly after passing beyond the central longitudinal plane of the car, but it is to be understood that it extends to the opposite side of said car, and at that end is 100 provided with such a hand-wheel 51 as is disclosed on the illustrated end.

Outside of one of the draft sills A, there is a ratchet wheel 50 mounted on winding shaft 11, which ratchet wheel is adapted to 105 be engaged by a pawl 49 secured to a pawl shaft 47 parallel and in proximity to said winding shaft. Pawl shaft 47 extends to

the side sills B and has its ends rotatably mounted therein and adjacent the side sills are operating handles 48 secured to pawl shaft 47, said handles being weighted to 5 maintain pawl 49 in engagement with ratchet wheel 50. When the chains 10 are wound up on shaft 11 to bring the doors into their closed position, pawl 49, when the pawl shaft is in the position shown, prevents 10 the rotation of shaft 11 in a chain-unwinding direction. Other means, of course, may be substituted for raising the doors without in any way affecting the operation of the door operating means as a 15 whole, but the means shown and described provide an economical and satisfactory way of doing so.

In the form of car illustrated, each door 20 55 is hinged at 56 to an intermediate sill C parallel with said sill B and separated therefrom by spacers E, and when closed the free edges of said doors 55 meet along the longitudinal center line of the car.

On the opposite sides of each door near 25 the free ends or meeting edges, are door supporting brackets 12 rigidly secured to said doors. When the doors are closed each pair of door supporting brackets 12 on the same side of the doors is engaged by a door 30 latch 13, which is pivotally secured to an oscillatory link or hanger 14 by pin 46, the hanger being rotatively mounted on a pin 15, which pin is supported in a bracket 16 secured to the draft sills A.

35 The door latches 13 are provided with forward extensions 17 adapted to occupy positions under the retaining shoulders 18 of the door-supporting brackets 12 when the latches 13 are advanced to a door-supporting 40 position as shown in Fig. 4 of the drawings.

If it be desired to discharge lading said door locks 13 are retracted as shown in Fig. 5, this being accomplished by applying a 45 suitable wrench to the non-circular end 57 of shaft 19 projecting outwardly from the side sill B, as shown in Fig. 2, it being understood that the opposite end of shaft 19 is provided with a similar projecting non-50 circular end 57.

Upon turning shaft 19 through the use of said wrench a crank 20 secured to said shaft will be partly rotated to swing a link 21, pivotally connected by pin 35 to the 55 other end of crank 20, from the position shown in Fig. 4 to that illustrated in Fig. 5. Link 21 being pivotally connected to heel portion 22 of the door latch 13 by pin 36, said door latch 13 will be swung away from 60 the door supporting brackets 12 to the position shown in Fig. 5, releasing one side of each door. That the opposite sides of said doors may be simultaneously released, another crank 27 is mounted upon shaft 19 65 between the center and intermediate sills

B and C, respectively, and to the outer end of crank 27 is pivotally connected a transmission rod 26, the other end of which is pivotally connected to a lever arm 34 extending from a gear sector 28.

70 Meshing with gear sector 28 is another gear sector 29 mounted upon shaft 19^a which is located on the side of the hopper opposite that adjacent shaft 19. Shaft 19^a is associated with door-locking mechanism similar 75 to that controlled by shaft 19, and has secured thereto a crank 20 pivotally connected by pin 35 to link 21, which in turn is pivoted by pin 36 to door latch 13 suspended from hanger 14, the latter being pivotally hung 80 from pin 15 supported in another bracket 16, which is secured to the draft sills A at the other end of the car. It is apparent, therefore, that a rotary movement given to shaft 19 will not only oscillate the crank 85 20 on that shaft to advance or retract door lock 13, but will also similarly actuate crank 27, moving transmission rod 26 to cause gear sector 28 to drive gear sector 29, whereby shaft 19^a is simultaneously partially re- 90 volved with shaft 19 to swing crank 20 carried by it, thereby advancing or retracting door latch 13 controlled by shaft 19^a in unison with the door latch 13 controlled from shaft 19.

95 The transmission arm 26 may be adjusted as to its length by means of a right and left hand threaded turnbuckle 31, or it may be continuous as desired.

The transmission gear 28, previously referred to, is mounted upon a short shaft 32, journaled in spaced brackets 33, which also receive the end of shaft 19^a upon which is mounted the gear sector 29, the gears being thus held in meshed relation. The lengths 100 of transmission arm 27 and arm 34 of transmission gear sector 28, and the pitch radii of the gear sectors 28 and 29, the lengths of the door latch 13 and door lock crank 20 are so proportioned as to transmit to shaft 19^a the 105 power required to complete the closing operation of the doors and to support them in closed position.

110 In each of the door locking mechanisms, link 21 is provided with extensions 23 and 24, which serve as stop shoulders and are adapted to engage, respectively, the shaft 19 and the shoulder portion 25 of the latch 13, whereby complete rotation of shaft 19 and consequently shaft 19^a is prevented. If the 115 forward extensions 17 of both door latches 13 are under the shoulders 18 of the door supporting brackets, and shaft 19 is given a partial rotation in a clockwise direction, shaft 19^a will, through the agency of gear 120 sectors 28 and 29 be given a contra-clockwise partial rotation, and the door latches 13 on both sides of the door will be withdrawn as shown in Fig. 5, whereupon the doors will 125 drop by gravity to a lading-discharging po- 130

sition, as indicated in dotted lines in Fig. 7 provided pawl 49 has first been disengaged from ratchet wheel 50, through the turning of pawl shaft 47 by its handle 48.

To return the doors to their closed position, and lock them in place, the hand-wheel 51 may be rotated, causing chain shaft 11 to revolve and wind thereupon the door raising chains 10, thereby lifting the doors to their closed position, or substantially so. The pawl shaft 47 having been revolved to throw pawl 49 into engagement with ratchet wheel 50 of the chain shaft, said doors are prevented from falling back to their open positions when the operator's grip upon hand-wheel 51 is released, and the door lock operating shaft 19 may then be partially revolved in a contra-clockwise direction.

Responding to such movement of shaft 19, crank 27 mounted on the latter operates transmission rod 26 to actuate gear sectors 28 and 29, the latter imparting to shaft 19^a a partial clockwise rotation. Cranks 20 secured, respectively, to shafts 19 and 19^a swing downwardly and toward the hopper from such positions as are indicated in Fig. 5 to those indicated by Fig. 4.

Links 21, door latches 13 and hangers 14 of the door locking mechanisms on opposite sides of the doors then assume the positions indicated in Fig. 4, the forward extension 17 of each door latch 13, being projected under the shoulders 18 of the brackets 12. Due to the door lifting chains being attached only to the brackets on one side of the door, the sides of the door remote from the points of chain attachment may tend to slightly sag, but the forward extension 17 of the door latches 13 have a wedging relation with the under side of retaining shoulders 18 of the door brackets 12, and as said door latches 13 are brought to their ultimate positions, the doors are drawn "home," effecting a complete closure of said doors.

In bringing the door latch 13 of each door locking mechanism to its ultimate position, pin 35 connecting crank 20 with link 21 is carried beyond a line extending through the centers of pin 36 and shaft 19 to prevent an accidental withdrawal of said door latch 13 from its door-supporting position.

Any effort on the part of the heel portion 22 of door latch 13 to rise and lift link 21 would be neutralized by the tendency of the pivot 35 to revolve about the shaft 19 in a contra-clockwise direction, as viewed in Fig. 4, causing the extension 23 of link 21 to bear against shaft 19, thus effectually locking all of the parts against any movement tending to release the doors.

The same action would take place in the other operating mechanism on the opposite side of the hopper, except, of course, pin 35 would tend to move in a clockwise direction, 65 nor can any possible swaying of link 21, due

to train movement, cause the complete retraction of the forward extensions 17 of latch 13 from its position under the retaining shoulders 18 of brackets 12, inasmuch as the shorter link or hanger 14 would tend to draw the forward extensions more firmly against said shoulders 18 of the door-supporting brackets.

With the arrangements shown, the power applied to shafts 19 and 19^a is delivered to the under side of retaining shoulders 18 of the door-supporting brackets 12 with greatly increased intensity, this multiplication of power being rendered possible by the system of leverage employed.

The door lock fulcrum pin 46 being nearer to the end of the forward extension 17 of door latch 13 than it is to the heel 22 thereof, transfers only a portion of the load to pin 36 for transmission to shaft 19, thus diminishing the effort required to unlock the doors.

Referring to Fig. 8, the hanger pins 15, previously referred to and shown in other figures, are seated within the sockets 36^a, 90 projecting inwardly from the side walls 38 of brackets 16, the pin seat portions and the front wall portions of said sockets terminating short of each other, to provide a socket 37 for the door lock hanger. The rear wall 95 of the socket is offset in the path of movement of hanger 14, as shown at 39, to clear the same and merges with the semi-cylindrical anti-friction roller seat 40 for an anti-friction roller member 41 (shown in Fig. 100 2), which is positioned within said seat 40 to provide a bearing for the door chains 10. Anti-friction roller 41 is put into place by inserting the same through an opening 42 in one of the side walls 38 of the bracket 16, 105 before said bracket is fitted to the car. After bracket 16 is positioned between the draft sills of the car, the webs of said sills prevent any endwise movement of roller 41.

Hanger pins 15 are retained within 110 sockets 36^a by means of removable keepers 43, such as cotter-pins, shown in Figs. 4 and 5, which are passed through openings 44, best disclosed in Fig. 8, provided in the upwardly extended socket portions 45 of the 115 brackets 16, and with the door hinges 56 carry the weight of the doors, the weight of the lading being sustained by said door hinges 56 and door latches 13.

It is apparent that I have devised a car 120 door operating mechanism peculiarly adapted to those types of cars in which center sills are not present, and whose hopper construction renders it difficult to apply ordinary door-raising and locking means. Furthermore, when it is only convenient or possible to raise the doors from a single side in such manner as to produce a sagging of the door portions remote from that side, resulting in a distortive closure, the arrange- 130

ment of the locks and their simultaneous operation is such as to produce an ultimate uniform closure. Said locks are characterized by swinging parts producing what may be termed a swing lock, and the swinging parts are connected in the form of a chain of linkage, the end members of which are oscillatively supported.

The locking mechanisms are conveniently located in protected and normally unused positions in the car illustrated, but, of course, may be differently disposed to the best advantage in other types of cars.

What I claim is:

- 15 1. In combination in a dump car, opposing doors adapted to close against each other, door-raising means, members on each side of said doors, swing door locks supported from the car framing to move in a direction other than that of the paths of said doors, each adapted to engage the members on opposing doors to hold the latter closed and means for operating said door locks.
- 25 2. In combination in a dump car, opposing doors, door-raising means adapted to close said doors against each other, members on each side of said doors, swing door locks supported from the car framing adapted to simultaneously come into co-operative relation with the members on opposing doors after the latter have been raised and to maintain said doors closed and operating means for said door locks.
- 35 3. In combination in a dump car, opposing doors hinged near the sides of the car, members on each side of said doors, door-raising means connected with a plurality of said members and adapted to close the doors against each other, swing door locks supported from the car framing to swing in and parallel with the plane in which said doors meet, and adapted to engage said members after the doors have been raised to maintain them closed, and operating means for said door locks.

4. In combination in a dump car, opposing doors hinged near and adapted to swing toward the sides of a car on opening, members on each side of said doors, door-raising means connected to the members at one side of said doors, door locks supported from the car framing adapted to be projected under portions of the members on both sides of the doors after the operation of said door-raising means and to carry said doors into a tight closure and operating means for said door locks.

5. In combination in a dump car, doors adapted to swing toward each other in closing, attachment devices connected to the sides of said doors, and door-raising means comprising a winding shaft supported by the sills of the car, means for rotating the same from the side of the car, flexible

members secured to said attachment devices and adapted to be wound on said shaft and retro-action prevention and permitting means for said shaft, and door-locking means.

6. In combination in a dump car, opposed hinged doors adapted to close against each other, members mounted on each door to oppose those on the opposite door, door-raising means and door-locking means provided with members having portions adapted to be projected between and into engagement with opposing door members to maintain said doors closed.

7. In combination in a dump car, draft sills at opposite car ends, a hopper interposed therebetween and extending therebelow, doors hinged near the car sides adapted to close near the transverse center of the car, door-raising means, swing door locks on opposite sides of said hopper supported from the adjacent draft sills and adapted to maintain said doors closed and means for simultaneously operating said door locks.

8. In combination in a dump car, draft sills at opposite car ends, a hopper interposed therebetween, doors adapted to close near the transverse center of the car, door-raising means, swing door locks for maintaining the doors closed supported from the draft sills, said hopper being also interposed between said locks, and means for simultaneously operating said door locks.

9. In combination in a dump car, doors adapted to close near the transverse center of the car, door-raising means, door locks located also near the transverse car center and provided with members movable longitudinally of the car to maintain a plurality of said doors closed, and operating means for said locks.

10. In combination in a dump car, opposing doors adapted to close against each other near the transverse center of the car, door-raising means, swinging door locks located also near the transverse car center and provided with members movable longitudinally of the car to support said opposing doors in closed position and means for actuating said locks operable from the car side.

11. In combination in a dump car, opposing doors adapted to close near the transverse center of the car, door-raising means, door-locks located also near the transverse car center and on opposite sides of said doors and provided with members movable into position to support said doors, transmission means for actuating the door-locks simultaneously and door lock operating means.

12. In combination in a dump car, spaced draft sills at opposite car ends, doors interposed between the sets of draft sills and

adapted to close near the transverse center of the car, members on the sides of said doors, door-raising means and door locks between said spaced draft sills comprising 5 hanger brackets, oscillatory hangers depending therefrom, rockable door latches carried by said hangers and means for projecting said latches into engagement with said door side members.

16 13. In combination in a dump car, doors adapted to close against each other at the center of the car, door-raising means, spaced draft sills adjacent the sides of said doors, door locks comprising hanger brackets secured 15 to and between said draft sills, oscillatory hangers depending therefrom, latches pivotally connected to the hangers, oscillatory cranks and links connecting said cranks and latches and means for moving said cranks 20 to project said latches to hold said doors closed.

14. In combination in a dump car, sills at the car sides, doors hinged thereto adapted to close near the center of the car, door raising means, draft sills on opposite sides of said doors, door locks supported from each set of draft sills, transmission means operably connecting the different door locks and supported from and lying adjacent to the 30 sills at the car sides and means for actuating said door locks operably connected with one of them.

15. In combination in a dump car, spaced sills at the car sides, doors hinged thereto adapted to close near the center of the car, door raising means, centrally located door locks on opposite sides of said doors, means extending transversely of the car for actuating each door lock, transmission means 40 located between the sills at a side of the car operably connecting the individual door lock actuating means and means for operating one of said individual actuating means to cause the operation of all of said actuating means.

16. In combination in a dump car, longitudinal sills near the car sides, centrally closing doors hinged thereto, door-raising means, door-supporting locks on opposite 50 sides of said doors, an actuating shaft for each lock and transmission mechanism paralleling said sills and connecting said shafts comprising a crank affixed to one shaft, suitably proportioned gearing connected with another shaft and means connected with said crank adapted to impart motion to said gearing.

17. In combination in a dump car, spaced longitudinal sills at the car sides, centrally closing doors hinged thereto, door-raising means, door-supporting locks on opposite sides of said doors, an actuating shaft for 60 each lock, transmission mechanism located between a pair of said spaced sills comprising a crank affixed to one shaft and a

gear member secured to another, a second gear member meshing with the first gear member, and an adjustable transmission member connecting said crank and second gear member and means supporting said 70 gears in proper relation to each other.

18. In combination in a dump car, longitudinal sills near the car sides, centrally closing doors hinged thereto, door-raising means, door-supporting locks on opposite 75 sides of said doors, an actuating shaft for each lock and transmission mechanism paralleling said sills comprising a crank affixed to one shaft and a gear sector secured to the other, a second gear sector meshing with 80 the first and provided with a crank, and a transmission member connecting both of said cranks.

19. In combination in a dump car, centrally closing doors, members secured to the 85 sides thereof, door-raising means, spaced longitudinal sills at the middle of the car, extending away from the sides of said doors, door locks between said sills each comprising a hanger bracket secured to the 90 sills, a hanger swung therefrom, a door latch pivoted to said hanger and adapted to engage said members when the doors are closed, an oscillatory crank and a link connecting said latch and crank and actuating 95 means for said crank, said hanger having increased binding against said brackets upon a tendency to move to an unlocking position when there is no corresponding movement of said actuating means. 100

20. In combination in a dump car, centrally closing doors, door-raising means and a door lock comprising a suitably supported swinging hanger, a door latch pivotally connected thereto, a crank, a link connecting 105 said crank and latch and a detent on said link, and an operating shaft connected with said crank and oscillative in opposite directions to advance or retract said latch to or from a door-supporting position, movement of said latch unaccompanied by an intentional movement of said shaft causing said link detent to engage said shaft and to prevent the withdrawal of said latch.

21. In combination in a dump car, spaced 110 sills, centrally closing doors extending transversely of said sills, door-raising means, a bracket between said sills comprising walls attached to the latter, transverse wall portions forming a seat for a 115 hanger pin and being interrupted and offset to form a hanger socket and keeper-receiving portions and a retainer for a guide for the door-raising means, a hanger-pin, keepers therefor, an oscillatory hanger, a 120 door latch, operating means therefor and a guide for said door-raising means.

22. In combination in a dump car, spaced 125 sills, centrally closing doors extending transversely of said sills, flexible door- 130

- raising members, a bracket between said sills comprising walls attached to the latter, transverse portions for supporting a hanger and a holder for an anti-friction 35 guide for said flexible members, a hanger pivotally suspended from the hanger-supporting portions, a latch carried thereby adapted to hold the doors closed and an anti-friction guide adapted to be inserted 10 into said holder through an aperture in one of said walls, said holder having an open portion to expose said guide, and means for operating said latch and flexible members.
- 15 23. In combination in a dump car, opposing doors adapted to close against each other, door-actuating means, suitably supported swing door locks adapted to approach each other to engage the opposing 20 doors to hold the same closed and operating means for said door locks.
24. In combination in a dump car, a set of oppositely opening doors, door-actuating means, suitably supported swing door locks 25 oppositely movable longitudinally of the car to and from said doors and adapted to support the same when oppositely moved and door lock operating means.
25. In combination in a dump car, opposing doors, door-actuating means adapted to move said doors toward each other, swing door locks, comprising pivoted latches and means for rocking the same, said latches being adapted to engage the opposing doors 30 after the latter have been partly closed and to maintain the doors closed and operating means for swinging said door locks and rocking said latches.
26. In combination in a dump car, doors 40 and door-actuating means, swing door locks adapted to be projected in a direction other than that of the path of the doors and to engage the latter after they have been partly closed and to force said doors to and maintain them in fully closed positions and door lock operating means.
27. In combination in a dump car, doors 45 and means adapted to raise the same into a non-uniformly distortive closure, door locks adapted to engage said doors and to cause the latter to be uniformly closed and to so maintain said doors.
28. In combination in a dump car, opposing 50 doors adapted to close toward the transverse center of the car, door-actuating means adapted to close the doors against each other, swing door locks adapted to engage said doors after the same have been raised and to maintain them closed and operating means 55 for said door locks.
29. In combination in a dump car, opposing 60 doors adapted to close against each other, door-actuating means, swing door locks located interiorly of the car sides and pro- vided with members movable longitudinally 65 of the car to support said opposing doors in closed position and means for actuating said locks operable from the car side.
30. In combination in a dump car, doors, door-actuating means, swing door locks operable in opposite directions and provided 70 with members movable oppositely longitudinally of the car to support said doors in closed position and operating means for said door locks.
31. In combination in a dump car, a plurality of doors, door-actuating means, separate door locks supported from fixed members and adapted to engage said doors, transmission means operably connecting the 80 separate locks to reversely actuate them to lock or to unlock said doors, and means for operating said locks and transmission means.
32. In combination in a dump car, doors provided with hinges the pivotal axes of 85 which extend longitudinally of the car, door locks spaced longitudinally of the car adapted to maintain said doors closed, an actuating device for each door lock, transmission mechanism operably joining said lock-actuating devices and means for operating the latter and said transmission mechanism.
33. In combination in a dump car, doors adapted to close toward the car center, door-actuating means, longitudinally extending 95 sills, spaced door locks supported from said sills and adapted to maintain said doors closed, transmission means operably connecting the door locks and means for actuating said door locks operatively connected 100 with one of them.
34. In combination in a dump car, doors, door-actuating means, fixed car structure portions, separate door locks supported 105 from the latter to simultaneously operate in different directions, longitudinally movable transmission means operably connecting said door locks and means connected to one of the door locks adapted to actuate all 110 of them.
35. In combination in a dump car, doors, door-actuating means, fixed car structure portions, separate swing door locks supported therefrom adapted to maintain said doors in closed position, transmission mechanism operable to reversely operate and to synchronize the movements of said door locks during an actuation thereof in one direction and means for actuating said door locks and transmission mechanism.
36. In combination in a dump car, doors, door-actuating means, centrally located door locks on opposite sides of said doors, means 115 extending transversely of the car for actuating each door lock, transmission means near a side of the car operably connecting individual door lock-actuating means and means for operating one of said individual actuat-

ring means to cause it to operate the remainder of said door lock-actuating means.

37. In combination in a dump car, centrally closing doors, door-actuating means, 5 door-supporting locks on opposite sides of said doors, an actuating shaft for each lock and transmission mechanism comprising a crank affixed to one shaft, suitably proportioned gearing connected with another shaft 10 and means connected with said crank and adapted to impart motion to said gearing.

38. In combination in a dump car, spaced longitudinal sills, doors provided with hinges parallel thereto, door-actuating 15 means, door-supporting locks on opposite sides of said doors, an actuating shaft for each lock, transmission mechanism comprising a crank affixed to one shaft and a gear member secured to another, a second gear 20 member meshing with the first gear member and an adjustable transmission member connecting said crank and second gear member and means supporting said gears in meshed relation.

39. In combination in a dump car, doors having hinges extending longitudinally of the car, door-actuating means, door-supporting locks each comprising an oscillatory hanger, a swinging latch adapted to move 30 longitudinally of the car to supportingly engage a door and means for swinging said latch out of engagement with said door.

40. In combination in a dump car, doors, door-actuating means, a swinging latch oscillatively connected therewith and adapted 35 to move in a direction other than that of the path of said doors to supportingly engage the latter and linkage for actuating said latch and operating means connected 40 with said linkage.

41. In combination in a dump car, doors, door-actuating means, door locks each comprising an oscillatory hanger, a swinging latch rockably connected therewith and 45 adapted to move in a direction other than that of the path of said doors to supportingly engage the latter and linkage for actuating said latch and means operable from the car side for actuating said linkage.

42. In combination in a dump car, doors, door-actuating means, door locks each comprising a vibratory latch, means for supporting and guiding said latch and latch-operating linkage, and operating means for 55 said linkage adapted to cause the same to move said latch into a door-supporting position from which unintentional retroaction of said latch is in opposition to that movement of said linkage-operating means required to withdraw said latch from the door-supporting position, said linkage-operating means being adapted to cause the withdrawal of said latch.

43. In combination in a dump car, doors,

door-actuating means, door locks comprising 65 suitably supported swinging door latches and latch-actuating linkage, rockable linkage-operating means, and interlockable means in said linkage and latches adapted to restrict said linkage-operating means to 70 rocking movements.

44. In combination in a dump car, a door, door-actuating means, a door lock comprising a chain of linkage both ends of which are oscillatively supported, a door-supporting extension on one link and means for actuating said linkage chain to move said extension into and out of a door-supporting 75 position.

45. In combination in a dump car, a door, door-actuating means, a door lock comprising a chain of linkage both ends of which are oscillatively supported, a door-supporting extension on one link and interlockable portions on some of the linkage elements 85 adapted to limit the movement of said linkage chain and means for actuating the latter to move said extension into and out of a door-supporting position.

46. In combination in a car having a door, a door lock comprising a latch having a door-engaging portion, an oscillatory hanger pivotally connected with said latch, a fixedly positioned hanger support and a pivot member connecting said hanger and support, said 95 hanger support being socketed to receive said pivot member and shaped to prevent endwise movement thereof, and door lock-actuating means.

47. In combination in a car having a 100 door, a door lock comprising a door-supporting latch, an oscillatory hanger therefor, a fixedly positioned hanger support and a pivot member connecting said hanger and support, said hanger support comprising a 105 trough-like socket portion for receiving said pivot member closed at its ends, said portion being interrupted and shaped to receive an end of said hanger, means co-operating with said socket portion to retain said pivot member and door lock-actuating means.

48. In combination in a car having, a door, a door lock comprising a door-supporting latch, an oscillatory hanger therefor, a hanger support and a pivot member connecting said hanger and support, said hanger support comprising an open pivot member-receiving portion fashioned to also uninterferingly receive a portion of said hanger and attachment means for securing 115 said hanger support in place adapted to prevent endwise movement of said pivot member and door lock-actuating means.

49. In combination in a car having a door and actuating means therefor, a door lock 125 comprising a latch, an oscillatory hanger therefor and a hanger support with which said hanger has a pivotal connection and

comprising means for securing said support in place in the car, an anti-friction device for the door-actuating means, and a retainer therefor combined with said hanger-support-
5 securing means, said anti-friction device being adapted to be inserted in and removed from said retainer only when said se-

curing means is disassociated with that which it is secured to, and door lock-actuating means.

In witness whereof I have hereunto set my hand.

JOHN M. ROHLFING.
